WORK BLASTING MACHINE

Wiltie I. Gladfelter, Hagerstown, Md., assignor
to Pangborn Corporation, Hagerstown, Md., a
corporation of Maryland

Application May 20, 1948, Serial No. 28,227

9 Claims. (Cl. 51—15)

1

This invention relates to work blasting machines and aims to provide a general purpose blasting machine particularly, but not exclusively, adapted for the blast treating or cleaning of the wide variety of sizes and shapes of castings dealt with in the average jobbing foundry, and which combines simplicity, great strength and great flexibility with economy in cost and in operation, without sacrifice of efficiency.

Other objects and advantages of the invention and of particular features thereof will be apparent from the following description of a preferred embodiment of the same.

With the foregoing general objects in mind, the invention comprises, among other things, an improved blasting machine which includes a housing enclosing a rotary work supporting table and means for blasting work supported thereby, the housing being openable with respect to both its vertical side and contiguous portions of its roof or top wall, so that heavy work may be carried to and removed directly from the central portions of the table by a crane or the like. More particularly this portion of the invention comprises a housing or casing having the blasting means and table completely enclosed therein and with a portion of the casing provided with pie-segment doors embracing contiguous portions of the side walls and segmental sections of the roof, and arranged so that in opened position they uncover over half the area of the table. The invention also comprises a simple efficacious machine in which the table is supported in such manner that its weight may be distributed directly to the underlying floor so that no pit is required for its installation. In its preferred form, the invention also comprises a new and unique arrangement for ventilating such a table; special provisions for cutting off the blasting operation if the doors are opened; advantageous means for securing and sealing of the doors; and an arrangement for allowing the blastant and detritus separating elements to operate during the unloading and loading of the machine, as well as during the blasting operation, thereby reducing the size and cost of the separator and the size and cost of the dust collector associated with the machine; as well as other novel features and combinations herein-after pointed out and claimed.

2

In the accompanying drawings showing a preferred embodiment of the invention:

Fig. 1 is a top plan view of the machine;

Fig. 2 is a side elevation thereof;

Fig. 3 is an enlarged detail section through the air inlet taken on line 3—3 of Fig. 1 as indicated;

Fig. 4 is an enlarged detail of the door bottom baffling and sealing means;

Fig. 5 is an enlarged detail of the table and 10 scraper support and drive means.

In the form shown in the drawings the blasting machine comprises a perforated rotatable work table 10, preferably carrying a rubber liner 11 perforated in coincidence with the table perforations, and which is mounted for rotation about a vertical axis 12 on suitable bearings exemplified at 13, Fig. 5.

As is best shown in Fig. 2 the table support is carried by transverse channel or other structural 20 members 14 which transfer the weight of the table and any loads carried thereby directly to the underlying floor 15. In this way, with no special pit or structural support, the load of the machine and its contents is distributed so that 25 the floor construction of the average foundry is sufficient to support the same.

As shown in Figs. 2 and 5, suitable seals 16 are provided between the bearings 13 and the blasting chamber hereinafter described, and the underlying portion of the table is provided with scraper blades 17 overlying a spent blastant collecting pan 18 and serving to push the collected grit or shot and detritus therefrom into an abrasive collecting hopper 19 which may be provided 30 with a screen plate 20 for screening out large nails or wires, etc., before the blastant and detritus are delivered to the boot of the elevating bucket conveyor 21 (Figs. 1 and 2).

The elevator conveyor extends upwardly from 40 the rear of the machine, preferably inside the housing thereof, to a position above the blastant supply hopper 22, and is driven by a motor 23 as through the belt drive 24.

The material raised by the elevator 21 is delivered to a separator 25 which may be of relatively simple construction, wherein the detritus, and the fines resulting from breakup of the shot or grit due to the blasting impact, are in considerable part separated from the reusable blastant 45 and delivered through a discharge pipe or dis-

charge conduit 26 to a suitable disposal receptacle 27, Fig. 1. The reusable grit delivered from the separator 25 is returned to the supply hopper 22 preferably through a screen 28.

As is shown near the bottom of Fig. 2, the elevator shaft or casing preferably communicates with the blasting chamber 29, and a baffled opening 30 may provide such communication.

In the illustrative embodiment the elevator shaft is employed as the air off-take conduit from the blasting chamber so that dust thrown up therein may be drawn off through the louvers 30 and delivered from the air outlet 31 to a suitable suction fan and dust-separating apparatus.

As dust is also removed in the separator 25 a further dust conduit 32 is provided which, as shown in Fig. 1, communicates with the discharge line leading from the outlet 31.

In the form shown, the blasting chamber 29 and the lower end of the elevator 21 are enclosed by a housing 33. This housing has a generally semi-oval front section embracing more than a diametrical half of the table 10, the top and side walls of which consist of contiguous doors openable to expose the same so that the hook of a crane may be brought directly above the center of the table to place and remove therefrom large and heavy castings and the like.

In the preferred form shown the openable sections constitute two contiguous arcuate doors 34 each embracing more than a quadrant of the table and hinged laterally to the remainder of the casing at 35.

Each door 34 in the form shown is of pie-segment form and comprises a section of side wall embracing more than a quadrant of the table and a corresponding section of top wall of the housing. The abutting edges of the two doors 34, and the jamb edges of the door ways and of the doors abutting thereagainst, are similarly flanged as indicated at 36 and 37; and one of each pair of flanged edges is provided with a suitable sealing means or packing such as the rubber or like gasket shown at 38, Fig. 4. No external flange corresponding to flange 36 is required at the top edge of the door as this edge is rigidified by the pie-segment shaped roofed portion.

Means is provided for securing the two doors in closed abutting relation. In the preferred form shown, this means comprises a toggle clamp or latch 39, Fig. 1, having main arms pivoted to one of the doors at 40 and supporting a shaft 41 to which are secured toggle dogs 42 and an operating handle 43. The toggle dogs 42 enter keepers 44 and, as these dogs and the handle 43 are swung about the shaft 41, draw the two doors closely together, compressing the packings associated therewith, and passing by dead-center so that the latch remains in closed position until a positive pull on the handle 43 releases the toggle action.

As is best shown in Figs. 2, 4 and 5, the table 10 has a flanged edge 45 which extends to or above the height of the lower casing portion 46, and the lower casing portion 46 is marginally reenforced at 47 and provided with a hanging skirt of rubber or the like 48 for protecting it from flying blasting particles. Liners 49 are also provided for the inner walls of the blasting chamber 29 which are exposed to wild flying abrasive during the blasting operation. As shown in Fig. 4, the liners for the door sections 34 are in the form of hanging sheets of rubber, and the lower edges thereof are held away from the door by baffle plates or brackets 50 which project from the

door walls 34 and over the lower portions of the housing 46-48 and are provided with a sealing ring 51 engageable therewith.

As is shown in Figs. 1 and 2 baffled air inlets 52 are provided in the roof of housing 33, and in the preferred form are carried by the roof sections of the door elements 34. As indicated in Fig. 3, these inlets preferably comprise a hood-shaped baffle 53 within the outer casing 52 and overlying the air inlet tube 54, and the lower end of the casing 52 may have outlet orifices between spacer elements 55 overlying baffles 56 to return to the blasting chamber any particles which may pass into the air inlet chamber.

Means for rotating the table is provided, preferably in the form of a friction drive roll 57 carried by a depending shaft 58 which is driven by motor 59 through suitable reduction gearing 60. The shaft 58 may be provided with various auxiliary elements, omitted for clarity, such as a universal joint, spring means or the like for pressing the roll 57 tightly against the table flange, and an overriding clutch enabling the table to be turned by hand after the driving power is cut off.

As is shown in Figs. 1 and 2, the housing 33 is provided with a blast stream projector 61 preferably of the airless centrifugal type, which is supported in a housing 62, herein carried in the top wall of the housing 33, the projector 61 being oriented to direct its fanlike blast stream diagonally across the table as shown at 63, Fig. 1, and against work pieces supported thereon.

In the form shown, the wheel is rotated in a direction to deliver the blastant in an undershot direction as indicated at 64, Fig. 2, so that it blasts both the top and side portions of the work, and the blast stream is directed diagonally of the blasting chamber so as to misalign it with the abutting jambs of the door members 34. Thus the principal quantity of wild flying abrasive strikes one of the door sections in the region 65, which region is preferably provided with a double layer of the rubber lining members 49 (Fig. 4).

In the illustrative embodiment the blast wheel 61 is driven by a motor 66 through a belt drive or the like 67, and the blasting particles are fed to the blast wheel from the supply 22 through a conduit 68 (Fig. 2), which is provided with a suitable abrasive flow controlling valve 69, best shown in Fig. 1. As is usual, the abrasive feed line 68 delivers to the wheels 61 in a generally axial direction and on the opposite side of the housing 62 from the drive shaft 70 (Fig. 1).

As is shown in Figs. 1 and 2, the hopper bottom 71 of the supply 22 is preferably provided with a second feed delivery valve 72 which controls the delivery of abrasive from the supply to a by-pass conduit 73. This conduit in the arrangement shown descends through the rear portion of the blasting chamber, is formed of rubber hose, and discharges directly to the spent abrasive hopper 19 and thus by way of the elevator 21 to the separator 25.

The valve elements 69 and 72, as shown, are preferably ganged and controlled by a common actuator 74 shown as a shaft rotatable by a crank and control handle 75, to at least two abrasive feeding positions. In the first or wheel feeding position, abrasive is fed from the supply 22 to the wheel 61 for projection thereby. In the second, or by-pass positions, the abrasive supply to the wheel is cut off and the abrasive is fed from the supply 21 through the by-pass 73.

Preferably one or the other of these feeds is employed whenever the machine is in operation. By this provision the abrasive from the supply 22 is continuously recirculated through the separator 25 during those intervals of time when the doors are open for inspection of the work, turning thereof to expose unblasted areas, and loading and unloading of the table. Thus the separating of detritus from the abrasive continues throughout the period of blasting and also throughout the intervening non-blasting periods. By virtue of this provision the size of the supply hopper 22 may be reduced, the necessary capacity of the separator 25 minimized, and because of the reduced capacity of the separator, the volume of dust delivered to the dust collector per unit of time is reduced enabling use of a smaller and less expensive dust collector.

Means is preferably provided operative to terminate the blasting operation by cutting off the supply of abrasive to the wheel, or by effecting quick stoppage of the wheel, on any initial movement of the doors 34 toward opened position. As shown in Figs. 1 and 2, this means comprises a stop switch 76 actuated by an abutment 77 carried by one of the doors 34 and adapted to cut off the supply of abrasive to the wheel and/or stop the wheel by any of the various arrangements known to the art. When a 6-foot table is employed a suitable speed of rotation of the table is about 2½-R. P. M. and the chamber may receive pieces as large as three feet high and six feet wide. As the table in effect is supported directly on the floor with the intervention of load spreading members, an extremely heavy load of castings, which may approximate five thousand pounds, may be carried by it on normal foundry floors without special strengthening provisions.

In use of the machine the operator places the work on the table, clamps the doors shut and turns on the wheel and table drive. The operator may then take time to prepare the next batch of work for loading, which he could not do if he had to control the blasting in a blast room. Moreover, the table rotates and the blasting occurs entirely within the enclosure formed by the stationary and swinging door portions of the housing. Thus harming of the operator by escape of abrasive from the front of the machine is eliminated, and the normal hazards of an ordinary blast room, where the operator comes into contact with rebounding abrasive, are avoided. After blasting for a certain length of time, the operator shuts off the wheel, opens the doors and examines the work, takes the pieces off that are thoroughly cleaned, and turns the pieces over that are not cleaned on all sides.

From the foregoing it will be apparent that the present invention provides an economical and versatile machine, combining the advantages of a blasting room and blasting table and including features cooperating for economy in its initial cost and cost of operation.

It is to be understood that the features of the invention may be embodied in specific forms other than those illustrated without departing from the principles or essential characteristics thereof. The embodiments shown are therefore to be considered as illustrative and not restrictive, the scope of the invention being defined by the appended claims. All modifications and changes which come within the meaning and range of equivalency of the claims are therefore intended to be included therein.

I claim as my invention:

1. In a blasting machine, and in combination, a work-supporting table; a housing enclosing a chamber about and above said table, said housing having door means openable to expose said table to facilitate loading and unloading thereof, a blast-stream projector positioned to direct its blast stream against work pieces supported on said table, an abrasive elevator extending through said housing adjacent said table, and communicating with said housing, means for sucking air from said housing through said elevator, and baffled air inlet means carried by the top of said housing for admitting air thereto.
15. 2. In a blasting machine, and in combination, a work-supporting table, a housing enclosing a chamber about and above said table, said housing having door means openable to expose said table to facilitate loading and unloading thereof, a blast-stream projector positioned to direct its blast stream against work pieces supported on said table, and means actuated by the initial opening movement of said door means for interrupting operation of said blast projector.
20. 3. In a blasting machine, and in combination, a housing surrounding a blasting chamber, work supporting means in said chamber, said housing having access means openable to enable work to be placed on and removed from said work supporting means, means for projecting blasting particles against work supported on said work supporting means, a blasting particle supply, means for separating blasting particles from detritus freed by the blasting operation and returning the particles to said supply, a conduit for feeding blasting particles to said projector, a by-pass for recirculating blasting particles through said separating means, and two path valve means associated with said conduit and said by-pass for feeding blasting particles from said supply to said conduit in one feeding position thereof and from said supply to said by-pass in the other feeding position thereof.
25. 4. In a blasting machine, and in combination, means defining a blasting chamber in which work is intermittently blasted, means for projecting blasting particles into said chamber, a blasting particle supply, means for collecting spent particles and detritus from said chamber, for separating detritus from the collected particles, and for returning the particles to said supply, a conduit for feeding blasting particles to said projector, a by-pass for feeding blasting particles to said separating means, and two path valve means associated with said conduit and said by-pass for feeding blasting particles from said supply to said conduit in one feeding position thereof, and from said supply to said by-pass in the other feeding position thereof.
30. 5. In a blasting machine, and in combination, a rotary table, a housing enclosing a chamber about and above said table, said housing having a generally semi-oval top wall and side wall portion embracing more than a diametric half of said table, the side and top walls of said semi-oval portion being in the form of swinging doors openable to afford vertical and lateral access to more than a diametric half of the table.
35. 6. In a blasting machine and in combination, a rotary table, a housing enclosing a chamber about and above said table, said housing having two abutting pie-segment doors each comprising a part of the side wall and a part of the top wall of the housing, said doors together embracing more than a diametric half of the table, and

means for propelling blasting particles into said chamber in a fan-shaped stream oriented to project its stream diagonally across the chamber and out of line with the abutting portions of said pie-segment doors.

7. A combination according to claim 6, said doors having flanged bottom and lateral edges, and being flange-reenforced at their top edges by the top wall segments thereof.

8. A combination according to claim 7, said doors comprising sealing means between their abutting edges, and having means for clamping together their abutting lateral edges.

9. A blasting machine comprising a cabinet, a rotative table mounted entirely within the cabinet, a blasting means carried by said cabinet and discharging across said table, the side and top walls of said cabinet comprising swingable

doors which can open widely enough to facilitate handling of castings being placed on or removed from said table, said doors comprising a portion of the top of said cabinet extending from the side thereof to a position overlying the central portions of the table.

WILTIE I. GLADFELTER.
